Attorney.

UNITED STATES PATENT OFFICE.

CHARLES W. SIEVERT, OF LOS ANGELES, CALIFORNIA.

OIL BURNER.

Application filed July 19, 1927. Serial No. 206,807.

This invention has reference to oil or other liquid fuel burners, and most particularly to a liquid fuel burner adapted particularly to use in a furnace, such for instance as a furnace of a water heater or an air heater. The invention is characterized mainly by improvements in the general type of liquid fuel burner shown in Patents Nos. 738,635 and 710,899, issued to me on Sept. 8, 1903, and October 7, 1902, respectively and also in my application Serial Number 52,481, filed August 31, 1925.

A general object of the present invention is to provide a burner of that type and character which is simple in form, efficient in operation and economical and easy of manufacture, and which offers as little obstruction as possible to the interior of the furnace and to the play of the flame above the burner.

The accomplishment of these and other objects and the advantages and novel features of the invention will be best understood from the following detailed description, reference for this purpose being had to the accompanying drawings, in which:

Fig. 1 is a plan of my improved burner;

Fig. 2 is a section on line 2—2 of Fig. 1 and showing a burner installed in a typical furnace;

Fig. 3 is a similar section on line 3—3 of Fig. 1;

Fig. 4 is a section on line 4—4 of Fig. 1;

Fig. 5 is a section like that of Fig. 2 but showing a modified form of burner; and

Fig. 6 is a section on line 6—6 of Fig. 5.

The burner includes characteristically a bowl 10 into the lower part of which there leads a liquid fuel feed pipe 11 through which liquid fuel is fed to the burner in proportion to its requirements. Preferably this fuel feed pipe extends up through the bottom of the bowl and projects somewhat above the inner bottom surface of the bowl. Bowl 10 is mounted and supported upon a plate 12 which is substantially rectangular in plan and is made of such size as to more or less completely fill the horizontal cross-section of the furnace chamber which is enclosed by the furnace walls 13. Bowl 10 may be substantially circular in plan but, in order to adapt a single standardized burner to furnaces of different sizes and shapes the bowl may have two opposite flat side walls 14 which parallel the longer side edges of mounting plate 12. The mounting

plate may have side extensions 12^a in segment form which may be breakable from the main body of the plate along breaking lines 15; so that if the parts 12^a are broken away the plate 12 is left in rectangular form. Other breaking lines may be provided in order to break the plate 12 down to any desired configuration to fit any shape of furnace. For instance circular breaking lines 15^a may be provided so that the plate may be broken down to circular formation in plan to fit a circular furnace chamber. Usually the mounting plate will be mounted in the furnace chamber by resting upon a flange or flanges such as illustrated at 20; but the mounting and support of the plate may be accomplished in any suitable manner. In any case it is desirable that the plate 12 substantially completely close off the furnace chamber so that all air which passes into the combustion chamber above the burner must pass through the burner in the manner now to be described.

The air pipe P extends across the upper part of the bowl. In its preferred form this air pipe is substantially semi-circular in cross-section, open at both ends at 30 and has a flat top wall 31. The air pipe rests in two semi-circular openings or notches 32 in the bowl wall; and in the form shown in Fig. 1, with the air pipe so in place, the upper flat wall 31 lies just above plate 12 and its projecting end portions 33 overhang plate 12 and rest upon that plate, as is best shown in Figs. 1 and 2. The air pipe is thus prevented from turning in its seat, and needs no fastening means to hold it in place. The air pipe has a central lower air opening 34 through which the air that enters the two opposite ends of the pipe flows downwardly over the center of the bowl and over the fuel pipe 11. The air being thus fed down onto the surface of the fuel, picks up the gases and vapors and the burning mixture moves outwardly and upwardly around the air pipe, combustion taking place around the air pipe and in the combustion chamber above the burner. The combustion space above the burner is free and unobstructed, the air pipe not extending into or occupying any portion of that space. At the same time the air pipe is located comparatively low in the bowl. It becomes heated by the combustion and in turn radiates heat to the liquid fuel which is fed into the bowl, and also functions as a

reservoir of heat which will act to keep fuel in the bowl hot during any temporary cutting off of combustion. If the burner should be temporarily turned out, the bowl and the air pipe hold a sufficient quantity of heat to warm the fuel which may be subsequently admitted to the bowl when it is desired to start combustion again; and the position of the air pipe close down to the fuel effectively aids in this function.

If desired, the air pipe may be equipped with auxiliary air holes 35 for allowing the feed of a certain amount of air out into the combustive mixture around the main air outlet 34.

Figs. 5 and 6 show a slightly modified form of air pipe arrangement. Here the air pipe P¹ is made to lie flush with the plate 12. The bowl is constructed the same as before except that, in the bottom of the semi-circular air opening 32 the bowl wall has small lugs 40 which enter notches 41 on the under side of the air pipe to keep the air pipe from turning away from its proper position. And in this form the upper flat wall 31 of the air pipe may be entirely flush with plate 12, as shown in Figs. 5 and 6.

I claim:

1. A liquid fuel burner of the character described, comprising a liquid fuel bowl with an open upper end and having at its upper edge a flange formation forming a burner plate, the wall of the bowl having air pipe openings extending below the burner plate, and an air pipe extending across the bowl and having open ends resting in the air pipe openings and having a central downwardly facing air outlet adapted to deliver air downwardly into the center of the bowl.

2. A liquid fuel burner of the character described, comprising a liquid fuel bowl with an open upper end and having at its upper edge a flange formation forming a burner plate, the wall of the bowl having air pipe openings extending below the burner plate, and an air pipe extending across the bowl and having open ends resting in the air pipe openings and having a central downwardly facing air outlet adapted to deliver air downwardly into the center of the bowl, the upper wall of the air pipe being flat and being substantially flush with the burner plate.

3. A liquid fuel burner of the character described, comprising a liquid fuel bowl with an open upper end and having at its upper edge a flange formation forming a burner plate, the wall of the bowl having air pipe openings extending below the burner plate, and an air pipe extending across the bowl and having open ends resting in the air pipe openings and having a central downwardly facing air outlet adapted to deliver air downwardly into the center of the bowl, the air pipe being substantially semi-circular in cross-section and having a flat upper wall substantially flush with the burner plate, and means to prevent rotational displacement of the air pipe with relation to the bowl and plate.

4. A liquid fuel burner of the character described, comprising a liquid fuel bowl with an open upper end and having at its upper edge a flange formation forming a burner plate, the wall of the bowl having air pipe openings extending below the burner plate, and an air pipe extending across the bowl and having open ends resting in the air pipe openings and having a central downwardly facing air outlet adapted to deliver air downwardly into the center of the bowl, the air pipe being substantially semi-circular in cross-section and having a flat upper wall substantially flush with the burner plate, and means to prevent rotational displacement of the air pipe with relation to the bowl and plate.

5. A liquid fuel burner of the character described, comprising a liquid fuel bowl with an open upper end and having at its upper edge a flange formation forming a burner plate, the wall of the bowl having air pipe openings extending below the burner plate, and an air pipe extending across the bowl and having open ends resting in the air pipe openings and having a central downwardly facing air outlet adapted to deliver air downwardly into the center of the bowl, the air pipe being substantially semi-circular in cross-section and having a flat upper wall substantially flush with the burner plate, and means to prevent rotational displacement of the air pipe with relation to the bowl and plate, said last mentioned means embodying extensions of the upper air pipe wall which rests upon the burner plate.

6. A liquid fuel burner of the character described, comprising a liquid fuel bowl with an open upper end and having at its upper edge a flange formation forming a burner plate, the wall of the bowl having air pipe openings extending below the burner plate, and an air pipe extending across the bowl and having open ends resting in the air pipe openings and having a central downwardly facing air outlet adapted to deliver air downwardly into the center of the bowl, the air pipe being substantially semi-circular in cross-section and having a flat upper wall substantially flush with the burner plate, and means to prevent rotational displacement of the air pipe with relation to the bowl and plate, said last mentioned means embodying interfitting formations between the air pipe and the bowl.

7. A liquid fuel burner of the character described, comprising a liquid fuel bowl with an open upper end and having at its upper edge a flange formation forming a burner plate, the wall of the bowl having air pipe openings extending below the burner plate, and an air pipe extending across the bowl and having open ends resting in the air pipe openings and having a central downwardly facing air outlet adapted to deliver air downwardly into the center of the bowl, the air pipe being substantially semi-circular in cross-section and having a flat upper wall substantially flush with the burner plate, and means to prevent rotational displacement of the air pipe with relation to the bowl and plate, said last mentioned means embodying interfitting lugs and notches on the air pipe and bowl.

8. A liquid fuel burner of the character described, comprising a liquid fuel bowl open

- at its upper end and having a flange formation around its upper edge forming a burner plate, the wall of the bowl having an air pipe opening through it located below the burner plate, and a horizontally extending air pipe having an open end resting in the air pipe opening and having an air outlet discharging downwardly into the center part of the bowl, the air pipe lying substantially wholly within the bowl and below the plane of the burner plate.
8. A liquid fuel burner of the character described, comprising a liquid fuel bowl open at its upper end and having a flange formation around its upper edge forming a burner plate, the wall of the bowl having two opposite air pipe openings and an air pipe open at its opposite ends and resting at its two ends in these two openings and having a central downwardly discharging air outlet, the air pipe lying substantially wholly within the bowl and below the plane of the burner plate.
9. A liquid fuel burner of the character described, comprising a liquid fuel bowl with an open upper end and having at its upper edge a flange formation forming a burner plate, the wall of the bowl having air pipe openings extending below the burner plate, and an air pipe extending across the bowl and having open ends resting in the air pipe
- openings and having a central downwardly facing air outlet adapted to deliver air downwardly into the center of the bowl, the air pipe having auxiliary air openings through its wall arranged around said air outlet and adapted to deliver air from the air pipe into the combustive mixture arising from the bottom of the bowl.
10. A liquid fuel burner of the character described, comprising a liquid fuel bowl open at its upper end and having a flange formation around its upper edge forming a burner plate, the wall of the bowl having an air pipe opening through it located below the burner plate, and a horizontally extending air pipe having an open end resting in the air pipe opening and having air outlet discharging downwardly into the center part of the bowl, the air pipe lying substantially wholly within the bowl and below the plane of the burner plate, the air pipe having auxiliary air openings through its wall arranged around said air outlet and adapted to deliver air from the air pipe into the combustive mixture arising from the bottom of the bowl.

In witness that I claim the foregoing I have hereunto subscribed my name this 23d day of June, 1927.

CHARLES W. SIEVERT.
